US00D879601S

(12) **United States Design Patent** (10) Patent No.: **US D879,601 S**
(45) Date of Patent: **** Mar. 31, 2020**

(54) **HEARING AID BATTERY PACKAGE**

(71) Applicant: **ENERGIZER BRANDS, LLC**, St. Louis, MO (US)

(72) Inventors: **William R. Dorr**, Madison, WI (US); **Christopher Harris**, York, ME (US); **Marek Kokoszka**, Fort Atkinson, WI (US); **Robert G. Lamasney**, Cross Plains, WI (US); **Ross J. Mack**, Dane, WI (US); **Daniel R. Teteak**, Madison, WI (US)

(73) Assignee: **ENERGIZER BRANDS, LLC**, St. Louis, MO (US)

(**) Term: **15 Years**

(21) Appl. No.: **29/624,349**

(22) Filed: **Oct. 31, 2017**

Related U.S. Application Data

(63) Continuation-in-part of application No. 15/694,490, filed on Sep. 1, 2017, now Pat. No. 9,954,208, which is a continuation-in-part of application No. 15/148,951, filed on May 6, 2016, now Pat. No. 10,093,469.

(57) **CLAIM**

We claim the ornamental design for a hearing aid battery package, as shown and described.

DESCRIPTION

FIG. 1 is a front top perspective view of the hearing aid battery package, showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

Any portion of the article depicted in broken lines forms no part of the claimed design.

Oblique lines show a transparent surface.

1 Claim, 5 Drawing Sheets
